UNITED STATES PATENT OFFICE.

GUY M. WHITCOMB, OF LYNN, MASSACHUSETTS.

CAN-OPENER.

1,052,297.

Specification of Letters Patent. Patented Feb. 4, 1913.

Application filed October 5, 1910. Serial No. 585,531.

To all whom it may concern:

Be it known that I, GUY M. WHITCOMB, a citizen of the United States, residing at Lynn, in the county of Essex and State of Massachusetts, have invented new and useful Improvements in Can-Openers, of which the following is a specification.

The invention provides an implement particularly designed for household use for opening packages containing goods which are generally marketed in sheet metal cans, the implement being of peculiar formation so as to provide ample leverage, a rest for the thumb or finger when manipulating the device for opening a can, a projection for holding the part of the top of the can or other cut portion from flying upward and a retaining point to hold the blade from slipping out of the cut.

20 A further purpose of the invention is the provision of an implement of the character aforesaid which may be constructed of sheet steel pressed and bent into required shape and while such formation is preferable it 25 is to be understood that the implement may be formed in any manner so long as it embodies parts in the relation herein specified and particularly defined in the claims.

Referring to the drawing hereto attached, 30 forming a part of the application, Figure 1 is a perspective view showing the application of the invention. Fig. 2 is an edge view of the implement. Fig. 3 is a side view of the device. Fig. 4 is a sectional view on the 35 line $z-z$ of Fig. 2.

Corresponding and like parts are referred to in the following description, and indicated in all the views of the drawing, by the same reference characters.

40 The implement comprises a body 1, which constitutes the handle, said body being elongated and comparatively thin and wide and consisting of a flat strip of metal, such as steel. A blade 2 is formed at one end of the 45 body 1 by folding an end portion of the strip upon itself, said blade having its opposite edges sharpened and converging to a point 3, which is dull upon its sides but tapered to provide a point for easily penetrat- 50 ing the top of the can or package to be opened. The point 3 is of some length and constitutes a retainer to prevent the blade slipping from the cut made in the can or package when opening the same, said point 55 engaging portions of the can bordering upon

the cut and thereby holding the blade in position and preventing possible slipping. The tapering end of the blade 2 is deflected outwardly from the body 1 so as to conform more nearly to the side walls of a round 60 can or package. The bent portion forming the fold between the body 1 and blade 2 is cut away at its ends, as indicated at 4, to provide a biting edge 5 and a space to receive the upper edge of the body of the can, 65 the edge 5 biting into the end of the can when oscillating the implement, thereby preventing slipping. The cutaway portions 4 are outwardly or forwardly converged, thereby resulting in throwing the biting 70 edges 5 inward from the outer edges of the blade 2 and body 1, with the result that portions of these parts form guards, which embrace opposite sides of the body of the can, thereby preventing lateral movement 75 of the implement when in operation.

A wing 6 projects laterally from the forward end of the body 1 and constitutes a rest for the thumb or finger of the hand to obtain a purchase upon which to press the 80 implement upon the can and hold it in place. The wing or rest 6 projects outwardly from the body 1 in an opposite direction from the blade 2 and also serves as a guard to prevent jagged edges of the can or body from 85 injuring the hand. A holder 7 projects outwardly from the blade 2 and its purpose is to engage the lid or part of the top or package when cut so as to prevent the partially separated portion from flying upward and 90 injuring the hand. The holder 7 may be provided in any manner, but it is preferred to form the same as a part of the strip from which the implement is constructed, said 95 holder being partially cut from the blade 2 and pressed outwardly therefrom.

The implement involves a simple construction and is free from joints since all the parts are of integral formation and the provision of the wing 6 and projection 7 prevents injury to the hand since the part 7 holds the cut portion of the can top from flying upward and the part 6 extends over the edge of the can, thereby preventing the rough edge from coming in contact with any part of the hand. The body 1 may be straight or slightly curved, the latter resulting in throwing the gripping portion away from the can, as will be readily understood. By having the blade 2 formed with two cut- 105 110

ting edges the implement may be used by oscillating the same either forwardly or rearwardly.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the embodiment thereof, I desire to have it understood that the device shown is merely illustrative, and that such changes may be made when desired as are within the scope of the claims appended heretc.

Having thus described the invention what is claimed as new, is:—

1. A can opener consisting of a strip of metal having an end portion tapered and folded upon itself to form a blade spaced from and lying substantially parallel with the body of the strip, both edges of the blade being sharpened, and having both ends of the fold cut away on oppositely inclined

planes to form fulera, and a holder located centrally of the blade and common to both edges thereof and to the said fulera and partly cut from the blade and pressed outwardly therefrom.

2. A can opener comprising a metal strip having an end portion tapered and folded upon itself to form a blade and having opposite edges of the blade sharpened, and having the ends of the folded portion cut away on oppositely inclined planes to form fulera, and having a portion of the blade partly cut and pressed outwardly therefrom to form a holder common to and located midway between the cutting edges of the blade and the said fulera, said strip being further provided at one edge near its folded end with a wing projecting laterally therefrom in an opposite direction to the blade to form a finger rest.

In testimony whereof I affix my signature in presence of two witnesses.

GUY M. WHITCOMB.
